UNITED STATES PATENT OFFICE.

CHARLES CAREY MANKER, OF OKLAHOMA, OKLAHOMA, ASSIGNOR OF ONE-HALF TO
MURRAY J. MORLEY, OF PITTSBURGH, PENNSYLVANIA.

RADIATOR.

1,344,422.

Specification of Letters Patent. Patented June 22, 1920.

Application filed April 5, 1917, Serial No. 160,036. Renewed May 19, 1920. Serial No. 382,686.

To all whom it may concern:

Be it known that I, CHARLES CAREY MANKER, a citizen of the United States, and a resident of Oklahoma, in the county and State of Oklahoma, have invented a new and Improved Radiator, of which the following is a full, clear, and exact description.

This invention relates to radiators and has for an object the provision of an improved construction whereby oil or gas burners may be used in the ordinary steam radiators now in common use for producing a proper steam heat.

Another object in view is to provide an improved attachment which may be connected to a specially prepared radiator or the ordinary radiators now in use, so as to maintain a steam pressure in radiators by the use of a burner maintaining a flame in a casing fitting into the radiator.

A still further object of the invention is to provide a heating element in connection with a radiator for heating water therein and means actuated by the steam in the radiator for controlling the volume to the heating element so as to produce automatically a uniform heat.

In the accompanying drawing:

The figure is a longitudinal vertical sectional view through a radiator with an embodiment of the invention applied thereto, said embodiment being partly in section for better illustrating the construction.

Referring to the accompanying drawing by numerals, 1 indicates part of the radiator, the same being formed from any desired number of sections 2 and 3 connected together in the usual manner. Arranged in

the opening 4 at the bottom of the sections 2 and 3 is a tubular member or pipe 5 threaded into the sleeve 6 at one end and to the elbow 7 at the opposite end. The elbow 7 discharges into a container or exhaust tank 8 having suitable openings 9 at the top.

The container or tank 8 may be empty or may be supplied with material for neutralizing the gases and burnt products of combustion passing through the elbow 7.

The sleeve 6 is not only threaded on to the pipe 5 but into the section 2 of radiator 1 and carries a housing 10 having an air opening 11 which is clamped in position by the fitting 12. Fitting 12 is provided with a plurality of openings 13 for admitting air,

the volume of air admitted being controlled by a washer 14 threaded on to the extension 15 of fitting 12.

A burner 16 is threaded in the extension 15 so as to project a short distance into the pipe 5, said burner being provided with a centrally arranged tube 17 formed with a bell-shaped opening 18 for receiving air and the pilot flame produced by the tip 19. By providing pipe 17 centrally of the burner 16 an annular gas chamber 20 is produced which discharges gas through a wire mesh covering 21, said gas being ignited by the flame through pipe 17 from the tip 19. As the flame is projected from the wire mesh 21 air is mixed therewith which enters the opening 13 and thereby produces a proper combustion of the gases. A sufficient quantity of air and a sufficient pressure is provided for the gases to produce a comparatively long flame for heating the full length of the pipe 5 whereby the water 22 is heated to the proper extent for producing any desired pressure of steam in the radiator. Preferably a sufficient quantity of water is provided through the filling plug 23 to maintain a proper amount of steam in the radiator and approximately the quantity of water shown in the drawing so that the tube 15 will always be submerged to a certain extent. By providing a heating member of this kind arranged as just described, and means for neutralizing the burnt gases in the chamber 8, substantially all of the heat is transmitted to the water 22 and from thence is caused to heat the radiator 1 through the action of the steam thereon so that a genuine steam heating effect is produced.

Any desired fuel may be used, as for instance, oil or gas, the structure shown in the drawing being adapted for gas which is supplied through pipe 24, which pipe may have a shut-off cock or valve arranged therein if desired. The gas through pipe 24 enters into the globular member 25 above the diaphragm 26, which diaphragm may be of any material, as for instance, metal, and clamped in position by the various bolts 27 which clamp the upper and lower sections 28 of the globular member 25 together. The upper section 28 of the globular member 25 is provided with a passageway 29 and a depending tubular member 30 which is normally held open by a spring 31 and the

pressure of gas from pipe 24. A threaded member 32 is provided for adjusting the tension of the spring 31 so as to maintain the same open even against a considerable pressure of steam.

When the device is first started the parts assume the position shown in the drawing and gas will pass from pipe 24 into section 28 and from thence through the notch 33, and, in fact, the entire bottom part of tubular member 30, into the passageway 29 and from thence into pipe 34. The notch 33 is provided in order that a small quantity of gas may be admitted into pipe 34 even when there is a high pressure of steam so that the burner will not be entirely extinguished at any time. A 3-way valve 35 is interposed in pipe 34 so that when the same is positioned as shown in the drawing gas may freely pass through the by-pass 36 to the tip 19 for maintaining the pilot light, but the main supply is shut off from the usual air mixture 37 and the burner 16. However, when the main passageway 38 of valve 35 registers with the pipe 34 the pilot will be maintained lighted and gas will be supplied to the chamber 20, a proper mixture being produced by the usual air mixer 37. The provision of this air mixer will allow the gas to properly burn while the air from openings 13 is for the purpose of supplying additional air in which the flame is maintained.

When the device has been used for some time and a considerable pressure of steam is produced, the same will begin to act upon the diaphragm 26 by reason of the fact that some of the steam will pass through the pipe 39 into the passageway 40 and from thence into the lower section 41 of the globular member 25. A notch 42 may be provided, if desired, so that steam will act upon the entire surface of the diaphragm continually and will force the diaphragm against the lower surface of the tubular member 30 when the predetermined pressure has been produced, whereby the gas pressure from pipe 24 and the spring 31 will be overcome. This will not fully shut off the gas by reason of the notch 33 but will reduce the flame to such an extent that there will be comparatively little heat produced so that the steam will be automatically reduced in pressure as the parts cool.

In order to completely obviate any possible danger a blow-off or relief valve 43 is provided which may be set to automatically open at any desired pressure. Arranged at a convenient point is the usual air valve 44 for allowing the escape of air during the first part of the heating of the radiator. The upper part of the sections of the radiator may be connected by short sections of pipe if desired, so that air may pass from

one section to the other and finally out valve 44, or the water level may be sufficiently low to allow the air to pass from one section to the other as is common in ordinary radiators now in use.

What I claim is:

1. In a heating attachment for radiators, a heating tube extending through the lower part of the radiator, means at the end of the tube connecting the tube with the radiator, said tube being open at one end, an apertured cap fitting over said opening, said apertured cap having a plurality of openings near the sides and a large central opening, means for regulating the amount of air passing through said first mentioned openings, a tubular burner arranged in said second mentioned opening, having a central passageway extending therethrough, means for projecting a small quantity of gas through said passageway for presenting a pilot-light, a gas mixer for supplying said tubular burner with a combustible gas, manually controllable means controlling the gas to said mixer and to said pilot-light, and an automatic controlling means controlling the gas supplied to said manually controlling means.

2. A heating attachment for radiators, comprising a tube extending through the lower part of the radiator, an exhaust tank connected with one end of the tube, means at the other end of the tube for regulating the admission of air into the tube, a tubular burner projecting into the said tube and having a centrally arranged tube whose outer end is bell-shaped, a mixer connected with the burner, a pipe connected with the mixer, said pipe being provided with a branch pipe leading to the bell-shaped end of the tube of the burner and having a burner tip, a valve in the first named pipe and controlling the passage of the fuel therethrough and through the branch pipe, and an automatic controlling means for controlling the supply of gas to the pipe in which the valve is located.

3. In a heating attachment for radiators, a tube extending through the lower part of the radiator, a fitting secured on one end of the tube and having a tubular and externally threaded extension, said fitting being provided with a plurality of air openings, a disk like member screwing on the extension of the fitting and controlling the passage of air through the openings of the fitting, a tubular burner secured in the extension of the fitting and having a centrally arranged passage, a burner tip at said passage, automatic means for controlling the supply of gas to the burner, and manually operable means for controlling the supply of gas to the burner tip.

CHARLES CAREY MANKER.
